FINGER SPACE GAUGE FOR BOWLING BALLS

Edward N. Norman, 3016 E. 98th St., Chicago, Ill.

Filed June 14, 1962, Ser. No. 70,545

Term of patent 3½ years

(Cl. D52—6)

FIGURE 1 is a perspective view of a finger space gauge for bowling balls showing my new design.

FIGS. 2 and 3 are edge views taken substantially on the lines 2—2 and 3—3 respectively of FIG. 1.

FIG. 4 is a cross sectional view taken on the line 4—4 of FIG. 2.

The depiction of the hand in FIG. 1 is for illustrative purposes only. The stippled portions of the gauge represent color contrast.

I claim:

The ornamental design for a finger space gauge for bowling balls, as shown and described.
